106,651

DESIGN FOR A WRAPPED EDIBLE CONTAINER FOR ICE CREAM OR THE LIKE

Aldo Colognori, Guttenberg, N. J., and Louis Werkstell, Brooklyn, N. Y.

Application March 17, 1936, Serial No. 61,676

Term of patent 3½ years

To all whom it may concern:

Be it known that Aldo Colognori and Louis Werkstell, citizens of the United States, and residents, respectively, of Guttenberg and Brooklyn, in the counties of Hudson and Kings and States of New Jersey and New York, have invented a new, original, and ornamental Design for a Wrapped Edible Container for Ice Cream or the like, of which the following is a specification, reference being had to the accompanying drawing, forming part thereof in which there is shown a perspective view of a wrapped edible container for ice cream or the like embodying our new design.

We claim:

The ornamental design for a wrapped edible container for ice cream or the like, substantially as shown.

ALDO COLOGNORI.
LOUIS WERKSTELL.
